UNITED STATES PATENT OFFICE.

EDWARD B. WESTON, OF DAYTON, OHIO, ASSIGNOR TO THE WESTON PAPER AND MANUFACTURING COMPANY, OF DAYTON, OHIO, A CORPORATION OF OHIO.

DISPLAY STAND.

Application filed October 24, 1927. Serial No. 228,385.

This invention is an improvement in display stands, and more particularly in stands of the foldable type designed to support a plurality of similar containers in similar 5 position.

The usual construction of stand includes a plurality of supports, in the form of trays or the like, upon which the articles, as for instance containers, set.

As a rule there is nothing to prevent lateral movement of the articles on the supports, which are particularly liable to displacement when in the form of containers with merchandise in bulk, such for instance 15 as candy, during the scooping up of the merchandise in dispensing.

Thus the dispenser must use one hand to steady the container while the other is operating the scoop, which is inconvenient, for 20 it is desirable that one hand be free to hold the bag or other receptacle into which the merchandise is transferred.

One of the primary objects of the present invention is the provision of a support of 25 the character specified, designed to hold a plurality of similar containers in similar relation, and easily accessible for dispensing, wherein each container is firmly supported against lateral displacement in any direction.

Another object is the provision of a stand capable of being folded into a relatively small and compact bulk for transportation or storage.

Another object is the provision of a lightweight stand of pleasing appearance, and capable of manufacture at a relatively small cost.

With these and other objects in view the 40 invention consists in the construction and novel combination of parts fully described hereinafter, illustrated in the accompanying drawings, and pointed out in the claims appended hereto, it being understood that various changes in the form, proportion, size and minor details of construction within the scope of the claims, may be resorted to without departing from the spirit of the invention.

In the drawings forming a part hereof:— Fig. 1 is a perspective view of the improved stand extended.

Fig. 2 is a similar view with the stand folded.

Fig. 3 is a detail in perspective of a part

of the stand, showing the cover connection.

In the present embodiment of the invention, the improved stand includes a pair of legs 1 of suitable material, connected at suitable intervals by cross bars 2, and pivoted 60 at their upper ends to a support 3, in the present instance a tray. Referring to Fig. 1, it will be seen that the cross bars are in rear of the legs, abutting the rear edges thereof and bent onto the outer faces, the 65 bent portions being riveted or otherwise connected to the legs.

The legs are pivoted to the ends of the support near the front thereof, and a bar 4 is pivoted to each end of the support near 70 the rear side, the bars 4 extending substantially parallel with the legs, in spaced relation, and of less length than the legs as clearly shown.

An easel support including legs 5 is 75 connected to the bars, each leg 5 being pivotally connected to the adjacent leg near the top thereof, as indicated at 6. A detachable connection is provided between each leg 5 and the adjacent bar 4, the connection being 80 indicated at 7, and including a screw bolt passing through registering openings in the leg and the bar, and held in place by a wing nut as shown.

The legs 5 of the easel support are connected by crossed inclined braces 8, engaging the rear edges of the legs, and having angular portions lapping on the outer faces of the legs, and riveted or otherwise secured thereto as shown at 9. The lower 90 ends of the legs 1 and 5 are preferably provided with rounded and ornamental feet shown at 10, and formed by suitable bending of the material of the legs.

The bars 4 are connected at suitable intervals by U-shaped or yoke members, each including a body 11 and arms 12 and 13. The arms 12 and 13 are pivoted to the bars 4 and to the legs 1. Each arm 12 and 13 as clearly shown is pivotally connected to a bar 100 4, and to a leg 1, the connections being indicated at 14 and 15 respectively, and the members are so positioned with respect to the cross bars 2 that each member is approximately midway between two adjacent cross bars.

In the present instance four cross bars 2 are provided, and there are three spaces between adjacent cross bars. In each of these spaces a U-shaped member is arranged, and 110

referring to Fig. 1, it will be seen that the arm 13 of each member is of greater length than the arm 12, so that the arm 13 has an extension 16 extending above the frame 5 constituted by the legs 1 and the cross bars when the stand is in extended position. Each of these extensions is longitudinally slotted as shown at 17 for a purpose to be described, and a frame 18 is supported by 10 each U-shaped member.

Each of the U-shaped members and the frame 18 carried thereby constitutes a support for a container, in the present instance a pail, and the frame 18 is shaped to fit the 15 container, being circular in the present instance to fit a pail. The bottom of the pail, when the stand is in use, rests upon the body 11 of the U-shaped member, and the frame 18 embraces the container to hold it in 20 place. It will be obvious that the frame will correspond in outline to the shape of the container it is adapted to hold.

Each of the frames 18 is held in a position with its plane at substantially a right 25 angle to the plane of the adjacent U-shaped support by means of a strut 19. Each of the struts 19 is pivoted to the frame 18 at the rear thereof, so that it may swing into the plane of the frame, as shown in 30 Fig. 2, or at right angles thereto, as shown in Fig. 1. The end of each strut remote from the frame has an angular perforated portion 20, which when the stand is extended, and the frame 18 at substantially a right angle 35 to the plane of the frame of the U-shaped member will lap upon the cross bar 2 just above the frame, and the perforation in the angular portion 20 will register with an opening 21 in the cross bar. Through this 40 opening a screw bolt is passed, and engaged by a wing nut, the connection being indicated at 22. The lower ends of the legs 10 are braced against the lowermost cross bar by inclined braces 23, and the easel support 45 is held in extended position by means of foldable struts 24, which are the arms of a yoke, including the arms and a body 25. The body 25 extends between the legs 5 of the easel support, and the arms are pivoted 50 on the rivets 9, near their connection with the body 25. The forward ends of the arms are adapted to be detachably connected with the legs 1 below the lowermost cross bar 2, the detachable connection indicated at 26 including a screw bolt and a wing nut as 55 shown.

During transportation or storage, the stand may be folded as shown in Fig. 2. The struts 19 are first released from the 60 cross bars 2, and swung into the position of Figure 2, that is in the planes of the frames 18. The connections 26 are then released, and the yoke 24-25 is folded back into the plane of the easel support. The bars 4 are 65 releasably connected with the tray, the con-

nection being indicated at 27, and including screw bolts and wing nuts. This connection is released and enables the bars 4 to move longitudinally with respect to the bars 1, and against the same, at the same time 70 swinging the U-shaped members 11-12-13 so that the arms 12-13 lie in substantial parallelism with the legs 1. Afterwards the frames 18 are turned into position of Fig. 2, and the stand is completely folded 75 into a compact form. Extending the stand is a reversal of these operations.

The containers, in the present instance pails, indicated at 28 when placed in display position have the tops removed, and 80 replaced by covers 29, which usually carry a plate of glass, to enable the contents of the containers to be inspected. Each of the covers is hinged to a strap 30 longitudinally slotted as shown at 31 to register with the 85 slot 17 of an extension 16.

After the container has been placed in the frame, the strap is brought into register with the adjacent extension, and a screw bolt is passed through the registering slots of the 90 strap and the extension, and is engaged by a wing nut, the bolt and nut being indicated at 32. This arrangement enables the cover to be swung out of position over the container to permit access to the contents 95 thereof.

What is claimed as new is:—

1. A display stand including a pair of legs connected at spaced intervals by cross bars, a U-shaped member between each pair of adjacent cross bars, each member comprising a body and arms, an open frame between the arms of each member, a pivotal connection between each arm, the frame and the adjacent leg, a link or bar pivotally connecting the corresponding arms of the U-shaped members near the body thereof, an easel support comprising a pair of rear legs braced against each other pivotally connected to the first named legs near the top thereof, means for detachably connecting the legs of the easel support to the links or bars to hold the stand extended, other means for detachably connecting the easel support to the first named legs near the lower end thereof, and a strut arranged between each frame and the next upper cross bar to hold the frame at substantially a right angle to its U-shaped support when the stand is extended, said strut being detachably connected with the 110 cross bar and pivoted to the frame.

2. A display stand including a pair of legs connected at spaced intervals by cross bars, a U-shaped member between each pair of adjacent cross bars, each member including a body and arms, an open frame between the arms of each member, a pivotal connection between each arm, the frame and the adjacent leg, mechanism for holding the U-shaped members in substantially parallel 125 130

planes, including an easel support for supporting the stand in upright position, and means for holding the frames in a common plane.

- 5 3. A display stand including a plurality of holders for similar articles, each holder including a support for the bottom of the article, and an open frame to encircle the article in spaced relation from the bottom support and connected to said bottom support, an easel supported frame in which the holders are journaled, and mechanism to hold the holders in like relation, said mechanism including means to hold the bottom supports in substantially the same plane, and the open frames in a common parallel plane.
- 10 4. A display stand including a pair of

spaced-connected legs, a plurality of holders pivoted between the legs, each holder including a bottom support for an article and a frame to encircle the article in spaced relation with respect to the bottom support, said support and frame being foldable with respect to each other into the plane of the frame, means for holding each holder in a definite position with respect to the frame, and with the plane of the holding frames in parallelism, and an easel support in connection with the stand and foldable with respect to the legs.

Signed at Dayton, in the county of Montgomery and State of Ohio this 20th day of October, A. D. 1927.

EDWARD B. WESTON.
